DESIGN FOR A COMBINED AUTOMOBILE GRILLE AND BUMPER ASSEMBLY OR SIM- ILAR ARTICLE

Edward Macauley, Grosse Pointe Farms, Mich.,
assignor to Packard Motor Car Company, Detroit, Mich., a corporation of Michigan

Application June 12, 1947, Serial No. 139,624

Term of patent 14 years

(Cl. D14—18)

To all whom it may concern:

Be it known that I, Edward Macauley, a citizen of the United States, residing at Grosse Pointe Farms, county of Wayne, State of Michigan, have invented a new, original, and ornamental Design for a Combined Automobile Grille and Bumper Assembly or Similar Article, of which the following is a specification, reference being had to the accompanying drawing, forming a part thereof.

The dotted line showing in Fig. 2 is for illustrative purposes only.

I claim:

The ornamental design for a combined automobile grille and bumper assembly or similar article, substantially as shown and described.

EDWARD MACAULEY.
